SURGICAL SPLINT

Application filed July 1, 1927. Serial No. 202,861.

Surgical splints heretofore designed for injured fingers and metacarpal bones and joints have been very cumbersome and bulky and the ordinary method of anchoring the inner end of the splint to the hand has been by strapping the splint to the palm by the use of adhesive tape passed around the hand. The "buckling" of the hand has defeated the effort at immobilization. Also as the sweat glands of the palm of the hand are very active such use of the adhesive tape has been unpleasant and unsanitary and necessitated frequent re-dressings with the consequent disturbance of the injured parts. Moreover, the blocking of the sweat glands on the back of the hand by the use of the adhesive tape tended to produce irritation and local skin infections. Also, this encircling of the hand with the adhesive tape interfered with the free use of the uninjured portions of the hand and produced a sensation of turgescence in all parts distal to the adhesive tape.

The object of my invention is to obviate the above faults by providing a very simple, light and inexpensive splint which may be anchored at its inner end to the wrist for properly supporting, protecting and immobilizing the injured part or parts, which splint may be applied with ease and dispatch and which will require (unless there be an open wound) no additional bandaging, packing or other dressing material and which may be used either alone or with additional splints of the same kind as required, without unduly interfering with the free use of the uninjured portions of the hand.

My invention comprises a longitudinally straight transversely curved splint of rigid sheet material having its concave inner surface provided with a suitable lining for relieving pressure discomfort or injury, the splint being of sufficient length to extend outwardly from a point adjacent the wrist along the metacarpal bone and finger to a point adjacent the outer end of the finger, preferably slightly beyond the same; a flexible element being provided at the inner end of the splint in position to be passed around the wrist and fastened for anchoring the splint to the wrist, adhesive tape being pref-

erably used to anchor the splint to the finger at the desired places.

A practical embodiment of my invention is represented in the accompanying drawings, in which

Fig. 1 represents the splint in side elevation, the free ends of the string for anchoring the inner end of the splint to the wrist being broken away.

Fig. 2 represents an inside plan view of the splint.

Fig. 3 represents a transverse section taken in the plane of the line III—III of Fig. 1, looking in the direction of the arrows.

Figs. 4, 5, 6 and 7 represent views showing different methods of applying the splint either singly or in pairs to the hand.

The splint comprises a longitudinally straight transversely curved piece of sheet metal 1 of sufficient rigidity, as, for instance, aluminum (for lightness and because it does not interfere with X-ray exposures), and of suitable weight or thickness. The splint preferably gradually decreases in width from a point near its tapered inner end 3 to its outer end 2, which outer end may be rounded, if so desired. The concave surface of the splint is provided with a lining 4 of felt or other suitable material of the desired thickness for relieving pressure discomfort or injury, said lining being permanently secured to the splint, as by glue or other adhesive.

The splint is of sufficient length to extend from a point adjacent the wrist along the metacarpal bone and finger to a point adjacent the outer end of the finger, preferably projecting slightly beyond the same. This splint is made long enough for the longest finger and the outer or inner end may be cut off when desired, to suit the shorter fingers. The width of the splint and its transverse curvature may be made to suit the average requirements so as to render the splint substantially universal in its application. The tapering of the inner end of the splint is for the more ready use of the same with adjacent splints of the same kind.

A flat string 5 or equivalent flexible element of suitable length is provided at the

inner end of the splint in ready position to be passed around the wrist and its free ends fastened together for anchoring the inner end of the splint thereto, strips of adhesive tape 6 being preferably used for carrying the splint to the finger at the places desired. The string 5 may be of absorbent material and is preferably slidably connected to the inner end of the splint, as, for instance, by passing the string through any desired pair of a series of pairs of holes 7, 8.

Some of the uses for which my improved finger and metacarpal splint is readily adaptable are—the effective support of the injured finger or metacarpal bone, or both; the effective immobilization of the joints or fractured bones; the maintenance of normal alignment after the reduction of fractures or dislocations; the correction of finger joints or metacarpo-phalangeal joints, which have stiffened in a state of "flexion" or "hyper-extension" and for the correction of "lateral" mal-alignment of any of the joints 25 of the thumb, index and little fingers, or of the metacarpo-phalangeal joints of the said fingers.

Some of the special advantages arising from the length of the splint and the anchoring of the inner end of the splint to the wrist are that a more perfect support and immobilization of the injured part or parts is obtained and the ability to properly support and immobilize not only the injured part of a finger but the corresponding metacarpal bone as well. Furthermore, the splint may be applied with more dispatch and less effort than those hereinbefore provided, the splint being capable of being applied to either the dorsal surface, the palmar surface, or splints in a pair to both. Other advantages arising from the splint hereinabove described are the facility with which a plurality of the splints may be used with 30 one string and the facility with which a readjustment and range of "play" may be secured by the loosening or tightening of the string around the wrist. Furthermore, it will not be necessary to carry a stock of 35 assorted sizes as the splint may be trimmed to suit the particular use required. Also by gradually reducing the width of the splint and by providing a series of sets of holes through the inner end of the splint for 40 slidably receiving the string, the splint is made practically universal in its application, as either end may be cut off and the string passed through the desired set of holes to properly anchor the splint to the 45 wrist.

What I claim is:—

1. A longitudinally straight transversely curved finger and metacarpal splint of rigid material having sufficient length to extend 50 outwardly from a point adjacent the wrist

along the metacarpal bone to the outer end of the finger to which it is to be applied, said splint gradually decreasing in width from a point near its inner end to its outer end, and means carried by the inner end of the 55 splint for anchoring it to the wrist.

2. A longitudinally straight transversely curved finger and metacarpal splint of rigid material having sufficient length to extend outwardly from a point adjacent the wrist 60 along the metacarpal bone to the outer end of the finger to which it is to be applied, the inner end of the splint having a series of pairs of holes therethrough and a flexible element passing through a selected pair of 65 said holes and adapted to be secured around the wrist to anchor the splint thereto.

In testimony, that I claim the foregoing as my invention, I have signed my name this 70 day of June, 1927.

REMBERT H. THIGPEN.
